No. 752,567.

Patented February 16, 1904.

UNITED STATES PATENT OFFICE.

WHEELER W. KERCHER, OF GOSHEN, INDIANA.

RAIL-JOINT.

SPECIFICATION forming part of Letters Patent No. 752,567, dated February 16, 1904.

Application filed September 19, 1903. Serial No. 173,864. (No model.)

To all whom it may concern:

Be it known that I, WHEELER W. KERCHER, a citizen of the United States, residing at Goshen, in the county of Elkhart and State of Indiana, have invented new and useful Improvements in Rail-Joints, of which the following is a specification.

This invention relates particularly to rail-way-rail joints of the scarf type, in which the abutting ends of the rails are scarfed and joined by fish-plates bridging the joint.

It is characterized by improvement with respect to the scarf and the use of a joint-chair supporting the abutting ends of the rails and engaging flanges on the lower edges of the fish-plates.

In the accompanying drawings, Figure 1 is a side elevation of the joint. Fig. 2 is a top view thereof. Fig. 3 is a cross-section.

Referring specifically to the drawings, the abutting ends of two rails are indicated at 6. These are scarfed at a bevel, as indicated at 7, preferably at forty-five degrees, so that ends will not have to be specially matched. The bevel or miter extends through the tread, web, and base of the rail. The abutting ends are lapped by the fish-plates 8, secured in the usual manner by through-bolts 9. The lower edges of the fish-plates are flanged, as at 10, and these flanges taper to an edge and lie upon the base of the rails.

At 11 a rail-chair is indicated bridging the

joint and having up and inturned flanges 12 at both edges, which overlie the edges of the flanges of the fish-plates and the edges of the rail-base.

The parts thus described form when assembled a securely bound and supported rail-joint. The bevel-joint avoids the objectionable bumping incident to square joints, and the rail-chair binds the fish-plates to the base of the rails and prevents lifting or spreading of the ends thereof.

Having thus fully described the invention, what is claimed as new is—

The combination of rails, having the abutting ends cut at a bevel extending through the heads, webs, and base-flanges, fish-plates lapping the said ends and having downwardly-beveled lower flanges extending over said base-flanges and terminating inwardly from the outer edges of the latter, a chair-plate extending snugly under the base-flanges of the rails and having upwardly-extending inturned flanges gradually reduced toward their free edges and overlapping the outer edges of the said base-flanges of the rails and the reduced edges of the lower flanges of the fish-plates.

In testimony whereof I affix my signature in presence of two witnesses.

WHEELER W. KERCHER.
